FINGERPRINT CARD OR SHEET HOLDER

Edward Kessick, New York, N. Y.

Application October 2, 1940, Serial No. 359,351

11 Claims. (Cl. 41—4)

This invention relates to new and useful improvements in a fingerprint card or sheet holder.

The invention proposes an article as mentioned which is characterized by a flat body, and a support strip mounted on the top of said body at its front end and having a rounded front portion and a flat downwardly and rearwardly extending rear portion, and means for holding a fingerprint sheet or card in different positions on said support strip. It is particularly intended to so hold the sheet or card that the support strip supports the area upon which the finger tips are fingerprinted. The purpose of having the flat downwardly and rearwardly extending rear portion of the support strip is that the four fingers of each hand may be conveniently rested or rolled thereon to obtain good plain or rolled fingerprints. However, it is necessary that the hand be turned around to fingerprint the thumbs.

Still further the invention proposes a novel construction for said sheet holding means.

Another object of the invention resides in a modification in which the support strip may be tilted to various positions so that its flat downwardly extending rear portion may assume various inclinations.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a plan view of a fingerprint card or sheet holder constructed according to this invention and illustrated with a fingerprint card or sheet mounted thereon.

Fig. 2 is an end elevational view of Fig. 1 looking from the left hand end.

Fig. 3 is a transverse vertical sectional view taken on the line 3—3 of Fig. 1.

Fig. 4 is a fragmentary plan view of a fingerprint card or sheet holder constructed in accordance with a modification of this invention.

Fig. 5 is a fragmentary enlarged vertical sectional view taken on the line 5—5 of Fig. 4.

Fig. 6 is a fragmentary enlarged elevational view looking in the direction of the line 6—6 of Fig. 4.

Fig. 7 is a fragmentary plan view of a fingerprint card or sheet holder constructed in accordance with a modified form of this invention.

Fig. 8 is a fragmentary side elevational view of Fig. 7 looking from the left hand side.

Figs. 9 and 10 are other views similar to Fig. 2, but illustrating other forms of the invention.

The fingerprint card holder, in accordance with this invention, includes a flat body 10 which has its front end fixedly mounted on a support or guide strip 11 in a manner so that the body 10 rests on a table 11' or the like and the strip 11 will prevent any slippage of the device when pressed against the edge of the table. A support strip 12 is mounted upon the top of said body 10 and at its front end has a rounded front portion 12^a continuing into a flat downwardly and rearwardly extending portion 12^b. A fingerprint sheet or card 13 is mounted upon the holder and has an area thereof which is to be used, engaged over and supported by said support strip 12. The flat body is provided with a means for adjustably holding the sheet 13 in position. The sheet 13 may be a part of a roll of printed paper used for fingerprinting or should preferably be stacked, one on top of the other, so that the uppermost sheet may be readily used for taking fingerprints.

The means mentioned in the previous paragraph includes a fingerprint sheet guide and holding strip 14 mounted on the front edge of the body 10 through which a section 13^a of the sheet 13 passes. Another fingerprint sheet guide and holding strip 15 is mounted upon the flat body 10 to the rear of the support strip 12. Another area of the sheet 13 passes through the strip 15. More particularly, the strip 14 comprises a strip body having a slot 14^a formed on its inner face. The sheet 13 passes through this slot. The strip 15 also comprises a strip body with a slot 15^a through which the sheet 13 passes. The flat body 10 is formed with an opening 10^b through which sheet 13 may be readily gripped and handled.

The fingerprint card and sheet holder is used in the following manner:

The sheet 13 is threaded through the guide and holding strips 14 and 15 so that an area thereof is tautly stretched over the support strip 12. A person standing to the front of the fingerprint card or sheet holder may easily place the four fingers of each hand simultaneously or five fingers separately upon that section of the fingerprint card or sheet which is rested on the support strip 12. The dot and dash lines 16 in Fig. 2 schematically indicate a finger properly placed on the fingerprint sheet. In this way good prints may be obtained of the four fingers of each hand. The sheet 13 may be slipped forwards or rearwards to various positions so that various areas

thereof are engaged over the support strip 12. In this way the entire sheet may be properly filled out.

In order to obtain good prints of the thumbs it is necessary that the hand be twisted around to a proper position to allow the thumb to come down in a position substantially the same as one of the four fingers. The feature of the guide and holding strips 14 and 15 resides in the fact that these strips will hold the fingerprint sheet or card tautly in position to conform with the shape of support strip 12, while at the same time it permits the sheet to be moved when required.

In Figs. 4 to 6 inclusive a modified form of the invention has been disclosed which distinguishes from the prior form in the construction of the means for holding the fingerprint sheet or card. This means is characterized by a fingerprint sheet guide and holding strip 14' which is mounted upon the front edge of the flat body 10 and which has a slot 14^a for the passage of the fingerprint sheet. The strip 14' is permanently attached to one leaf 18^a of a hinge 18 which has its other leaf 18^b pivotally mounted on the front edge of the body 10 by a pintle screw or fastening element 19. The remote end of the strip 14' is releasably held in position by a headed stud 20 which is urged outwards by a coaxial spring 21 mounted thereon. The stud 20 has an internal head 22 engaging a bayonet slot 23 formed in the front of the flat body 10. The arrangement is such that the strip 14' may be pivoted to disengage the head 22 of the stud 20 from the bayonet slot 23 and then the strip 14' may be hinged open. This facilitates the engagement of the fingerprint sheet through the slot 14^a.

The flat body is also provided with a fingerprint sheet guide and holding strip 15' mounted upon the top of the flat body 10 to the rear of the support strip 12. This strip 15' is hingedly and pivotally supported at one end by a hinge 18. The hinge 18 has a leaf 18^a permanently attached to the strip 15' and another leaf 18^b which is pivotally mounted on the body 10 by a pintle screw or other fastening element 19. The other end of the strip 15' is provided with a headed stud 20 having an inner head 22. A spring 21 urges the stud 20 in one direction. The head 22 is cooperative with a bayonet slot 23' formed in the body 10. The arrangement is such that the strip 15' may be pivoted to disengage the head 22 from the bayonet slot 23' and then the strip 15' may be hinged upwards to an open position about the hinge 18.

In other respects this form of the invention is similar to the previous form and like parts are identified by like reference numerals.

In Figs. 7 and 8 another form of the invention is disclosed which distinguishes from the form shown in Figs. 1-3 in the fact that there is a support strip 12' mounted upon the flat body 10. This support strip 12' is adjustably mounted. The strip 12' is formed from heavy sheet material. It has a curbed front portion 12^{aa} and a flat downwardly and rearwardly extending rear portion 12^{bb}. The rear end of the rear portion 12^{bb} is provided with a pair of lugs 25 which are pivotally connected by pintles 26 with brackets 27 mounted on the flat body 10.

Lugs 28 are mounted along the sides of the support strip 12'. These lugs have elongated slots 29. Links 30 extend across the slots 29. These links 30 have elongated slots 31. A screw and wing nut 32 engage through each pair of

slots 29 and 31. Each link 30 is pivotally supported by a pintle 33 at its bottom end on a stationary bracket 34 mounted on the flat body 10. In other respects this form of the invention is similar to the previous forms.

The use of this form of the invention is identical to the prior form. However the inclination of the support strip 12' may be changed to better suit a person being fingerprinted. It is merely necessary that the wing nuts and screws 32 be loosened and then the front edge portion of the support strip 12' may be moved upwards and downwards to change the inclination of the flat downwardly and rearwardly extending rear portion 12^{bb}. The screws and wing nuts 32 may then be tightened to hold the support strip 12' in its new position.

In Fig. 9, in place of the support strip 11, a downwardly extending finger 11^a of a metal plate support strip 12'' is provided for keeping the fingerprint card holder against a table or the like and to prevent the device from slipping. This finger 11^a may be raised or lowered and simultaneously the metal plate support strip is also raised or lowered to different positions.

A loop 35 is secured to the edge portion 10' of the body 10'' to guide the fingerprint sheet. Raised portions 12^d along the side edges of the support strip 12'' help to keep the fingerprint sheet in position together with the strip 15.

In Fig. 10, the body 10''' and the inclined portion 36 are made to form an integral portion together with loop 35' and the strip 15'. This form of the invention may be made of composition or any other suitable material.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A fingerprint card holder, comprising a flat body, a fingerprint sheet guide and holding strip mounted on the front edge of said body, a support strip mounted on the top of said body at its front end and having a rounded front portion and a flat downwardly and rearwardly extending rear portion, and a fingerprint sheet guide and holding strip mounted on said flat body to the rear of said support strip.

2. A fingerprint card holder, comprising a flat body, a fingerprint sheet guide and holding strip mounted on the front edge of said body, a support strip mounted on the top of said body at its front end and having a rounded front portion and a flat downwardly and rearwardly extending rear portion, and a fingerprint sheet guide and holding strip mounted on said flat body to the rear of said support strip, each of said strips comprising a strip body with a slot.

3. A fingerprint card holder comprising a flat body, a support strip mounted on the top of said body at its front end and having a rounded front portion, and a flat downwardly and rearwardly extending rear portion, and means for holding a fingerprint sheet in various positions across said support strip.

4. A fingerprint card holder comprising a flat body, a support strip mounted on the top of said body at its front end and having a rounded front portion, and a flat downwardly and rearwardly

extending rear portion, and means for holding a fingerprint sheet in various positions across said support strip, said means comprising fingerprint sheet guide and holding strips mounted on said body to the front and to the rear of said support strip.

5. A fingerprint card holder comprising a flat body, a support strip mounted on the top of said body at its front end and having a rounded front portion, and a flat downwardly and rearwardly extending rear portion, and means for holding a fingerprint sheet in various positions across said support strip, said means comprising fingerprint sheet guide and holding strips mounted on said body to the front and to the rear of said support strip, each guide and holding strip being hingedly and pivotally mounted at one end, and means for releasably holding the other ends of said guide and holding strips, whereby the guide and holding strips may be pivoted upwards to facilitate the engagement of a fingerprint sheet or card therebeneath.

6. A fingerprint card holder, comprising a flat body, a fingerprint sheet guide and holding strip mounted on the front edge of said body, a support strip mounted on the top of said body at its front end and having a rounded front portion and a flat downward and rearwardly extending rear portion, a fingerprint sheet guide and holding strip mounted on said flat body to the rear of said support strip, and means for raising and lowering the front portion of said support strip for changing the inclination of the rear portion.

7. A fingerprint card holder, comprising a flat body, a fingerprint sheet guide and holding strip mounted on the front edge of said body, a support strip mounted on the top of said body at its front end and having a rounded front portion and a flat downward and rearwardly extending rear portion, a fingerprint sheet guide and holding strip mounted on said flat body to the rear of said support strip, and means for raising and lowering the front portion of said support strip for changing the inclination of the rear portion, comprising means for hingedly mounting the support strip at its rear end, and means for holding the front end of the support strip in various fixed positions.

8. A fingerprint card holder, comprising a flat body, a fingerprint sheet guide and holding strip mounted on the front edge of said body, a sup-

port strip mounted on the top of said body at its front end and having a rounded front portion and a flat downward and rearwardly extending rear portion, a fingerprint sheet guide and holding strip mounted on said flat body to the rear of said support strip, and means for raising and lowering the front portion of said support strip for changing the inclination of the rear portion, comprising means for hingedly mounting the support strip at its rear end, and means for holding the front end of the support strip in various fixed positions, including screws and wing nuts which may be loosened to permit a change of the position of the support strip.

15. 9. A fingerprint card holder, comprising a flat body, a fingerprint sheet guide and holding strip mounted on the front edge of said body, a support strip mounted on the top of said body at its front end and having a rounded front portion and a flat downward and rearwardly extending rear portion, and a fingerprint sheet guide and holding strip mounted on said flat body to the rear of said support strip, said support strip being adjustable for setting the same into the natural condition of the fingers which are to be fingerprinted.

30. 10. A fingerprint card holder, comprising a flat body, a fingerprint sheet guide and holding strip mounted on the front edge of said body, a support strip mounted on the top of said body at its front end and having a rounded front portion and a flat downward and rearwardly extending rear portion, and a fingerprint sheet guide and holding strip mounted on said flat body to the rear of said support strip, said support strip being adjustable for setting the same into the natural condition of the fingers which are to be fingerprinted, and means for preventing the holder from sliding.

35. 11. A fingerprint card holder, comprising a flat body made of plastic material, a fingerprint sheet guide and holding strip on the front edge integral with said body, an inclined support strip on the top of and integral with said body at its front end and having a rounded front portion and a flat downward and rearwardly extending rear portion, and an integral fingerprint sheet guide and holding strip on said flat body to the rear of said support strip.

EDWARD KESSICK.
